Attorney

UNITED STATES PATENT OFFICE.

FRANK J. KRISTOFER, OF ST. PAUL, MINNESOTA, ASSIGNOR TO BROWN & BIGELOW,
OF ST. PAUL, MINNESOTA, A CORPORATION OF MINNESOTA.

ATTACHMENT OF FACE PLATES.

Application filed July 13, 1925. Serial No. 43,281.

My invention relates to attachment of precious metal face plates on pocket knives and other pieces of cutlery such as paper knives and letter openers where it is desired to provide a handle formed with a cover of precious metal such as gold, silver or other material, when it is desired to attach the face plate to hold the same firmly secured to provide a very attractive handle which can be decorated on the surface of the same.

A feature of the invention resides in the attachment of precious metal face plates to the sides of a knife without penetrating through the face plate with a rivet, yet securely attaching the face plate to the handle or sides of the knife.

It is also a feature of my invention to provide means of attaching face plates which permits the face plates to be engraved or decorated on the surface and without requiring any soldering or riveting means which will mar the face plates. It is quite important in the manufacture of articles of cutlery where it is desired to provide a face plate of precious metal to have means for attaching the plate to the sides of the article of cutlery and over the edges of the same so that the sides of the knife or articles of cutlery, which are usually formed of brass or other cheaper material which are not desirable to be exposed, are thus completely covered, forming a handle with a covering or face plate of metal to make a very attractive article of cutlery.

It is also a feature of my invention to provide a paper knife having spring means formed integral with the knife blade extending in between the sides of the handle of the knife and being pivotally adapted, with one end free, to form the spring member adapted to hold a knife blade in open or closed position, projecting from or concealed within the handle of the knife so that it is not necessary to provide an extra spring member between the sides of the handle but the blade of the paper knife is extended and forms this spring means within the sides of the handle.

Heretofore these plates have been secured by rivets which is undesirable because they must pass through the sides and be exposed to the outside of the plate. It is very expensive to use gold or silver rivets, or rivets which would conform with the precious metal forming the cover and side plates and it is obvious

that it is not practical to use this means of construction by reason of the softness of the material and undesirable results eventuating from such use of precious metal for the retaining pins or rivets to hold the sides of the handle to the knife. These pins or rivets are used to hold the plates on the knife, or article of cutlery, and in so doing they must be strong and durable to permit use without appreciable wear. Soldering means have also been used to attach these plates to the sides of the cutlery and this is unsatisfactory as the acid or fluxing means used for soldering is inclined to cause corrosion of the metal or steel of the knife blade and discoloring of the precious metal sides.

My invention obviates these difficulties heretofore apparent and provides means of attachment for face plates on an article of cutlery which is very desirable.

These features together with other details of construction will be more fully and extensively pointed out in the specification and claims.

In the drawings forming part of these specifications:

Figure 1 is a side view of a paper or letter opener knife with a knife blade formed in the handle.

Figure 2 is a side view of a pocket knife illustrating my invention.

Figure 3 is a section on the line 3—3 of Figure 1.

Figure 4 is a section on the line 4—4 of Figure 2.

Figure 5 illustrates the side plates of precious metal, the filler member and one of the sides in separated position from the knife or article of cutlery showing relative consecutive position in perspective.

Figure 6 is a section on the line 6—6 of Figure 5 in the drawings.

Figure 7 is a section on the line 7—7 of Figure 5 in the drawings.

My invention relates to means of attaching the precious metal side plate A to an article of cutlery, such as paper knife B or pocket knife C, illustrated in the drawings.

The side face plates A have their body portion 10 formed of precious metal, such as gold, silver or other suitable precious metal, either in their entirety throughout the thickness of the same, or of a plated or filled nature, so that the outer surface which will be

exposed when the plate is attached to the article of cutlery will be of precious metal.

The face plate A has its body portion 10 formed with depending side walls 11 extending about the entire periphery of the same. In the first formation of the side plates A the side walls 11 depend in angular position from the body portion 10, either at right angles therefrom or any other suitable position so that the sides 11 can be rolled inward to clamp the face plate A to the side plates or cheek member 12 of the knife B or C or other articles of cutlery.

It is an important feature of my invention to provide means of fastening my face plates and so construct the side plates 13 as to provide a bevelled surface adjacent the blade backs of the knife. This construction permits free access to the blade of the knife so that it can be readily withdrawn. When it is desired to have the back of the blade substantially flush with the casing for the sake of the better appearance of the article, a bevelled edge adjacent the back of the blade provides 25 a means of giving access to the same so that the blade can be easily engaged, yet giving a neat and attractive appearance.

The side plates 12 are formed of metal such as brass or any other suitable metal and have 30 the side edges about the entire formation of the same bevelled at 13 to incline inwardly toward the center recess 14 in which the knife blade 15 is concealed, when the blade is in closed position. Thus the side plates 12 form 35 the side or cheek members of the knife, or article of cutlery, and the bevelled edge 13 extending about the same is adapted to receive the depending edges or sides 11 of the face plates A and when these plates are held 40 in place the edges or sides 11 are rolled or compressed into close engagement with the bevelled sides 13 so as to rigidly attach the face plates to the side members 12 to form 45 the covering plates for the article of cutlery such as the knife B or the pocket knife C.

Where it is desired to provide the handle of the knives B or C with a heavy thick formation, a filler plate or member 16 is used which is inserted between the face plates A 50 and the sides 12 of the knife. This gives the appearance of a very thick handle member and obviates the necessity of using a thick face plate A or a heavy side plate 12.

In making up my article of cutlery the side plates 12 are secured by the rivets 17 which extend through the openings 18 in the side plate 12. These rivets 17, or pins, hold the plates 12 against the spring member 19 of the knives B or C. The pins being riveted 55 on the ends so as to firmly secure the plates 12 to the same. In the case of a pocket knife the blades 15 of the same are riveted or pivotally held between side plates 12 by the end pin 17 while the center pin 17 holds the 60 spring which operates the blades to hold the

same in open or closed position. These pins 17 are covered as is also the side plates 12, to conceal approximately the entire exposed surface and to form the side plates of precious metal by the side plates A.

The side plates A are readily and easily attached over the beveled sides 13 of the plates 12 by rolling the depending walls 11 tightly into engagement with the beveled surface 13. It is also evident that these plates 70 A can be attached by pressing the sides 11 inward to hold the same over the wedge shape of the side plates 12. This locks the plate A without injuring the outer precious metal surface or the outer surface where the side plate A is formed entirely of precious metal and provides means of attaching plates to form a very attractive piece of cutlery. This formation of my attachment of face plates is of extreme importance in my invention because it permits the face plates to be stamped and to be formed before it is attached to the side plates 12 and it is evident that such a formation and construction is of 80 importance in making up an article of manufacture of this nature.

The face plates A must not come off after they are attached. They must be neatly and carefully formed and by means of my construction, the edges are turned in over the sides 12 of brass, or other cheaper material which is equally as good, if not better, to provide the side formations of the article of cutlery and thus an article is formed which provides a handle and face plate which is 90 very desirable for articles of this nature.

My means of securing the face plates and the formation of my knife is inexpensive as compared to some methods which have been employed heretofore and the results are highly preferred over any known methods in so far as I know and the results which I have obtained in the making of these knives have been very satisfactory and gratifying in the demand for articles of cutlery made up in this 100 manner.

In the construction of paper knives B, as illustrated, the blade 20 is formed of steel and is provided with an integral formation of the spring member 19 which extends between the sides 12. The outer free rear end 21 of the spring 19 is riveted through the sides 12, but is pivotally held by the center rivet 17' and is formed with a thinner portion 22 which permits the free flexing of the end 21 in the operation of the knife blade 15 over the free end to form the spring of the paper knife B for the knife blade held within the handle of the same. This is a very desirable construction for paper knives and I desire to set forth this form of my invention as it provides an economical, yet very effective means of manufacture. This construction in conjunction with the face plates A provides a paper knife 115 of a most attractive nature, having precious 120 metal by the side plates A.

metal handles and a steel blade 20 projecting from the same, giving a wonderful appearance to the finished article.

In accordance with the patent statutes I have described the principles of operation of my invention, together with the principal formation and construction of the same which I have shown in one formation in my drawings and I desire to have it understood that these 10 are only illustrative and that the invention can be carried out by other means and applied to uses other than those above set forth within the scope of the following claims.

I claim:

15 1. Face plate attaching means for articles of cutlery including bevelled edge side plates, metal face plates adapted to cover said side plates, and inwardly turned side walls adapted to engage said bevelled edges to provide a 20 recess to the blade to permit easy withdrawal of the same.

2. Precious metal side plate attaching means for pocket knives including inwardly

bevelled side plates adjacent the blade, precious metal cover plates for said side plates, 25 having a peripheral edge turned over said bevelled edges of said side plates to provide a space which allows access to the blade for opening the knife.

3. An article of cutlery including base 30 plates, adjacent the blade thereof, inner marginal bevelled edges on said base plates, a precious metal outside plate having a marginal edge adapted to engage said marginal bevelled edge of said base plate to provide a 35 marginal recess which permits free access to the blade.

4. A knife including a handle having a base plate, an inwardly inclined marginal edge formed on said base plate, a cover plate adapted to extend over said base plate and said inwardly inclined marginal edge whereby access to the blade for opening the knife is provided. 40

FRANK J. KRISTOFEK.
